UNITED STATES PATENT OFFICE.

GEORGE L. STARR, OF OTEGO, NEW YORK.

CULINARY LIFTER.

SPECIFICATION forming part of Letters Patent No. 769,028, dated August 30, 1904.

Application filed April 22, 1902. Serial No. 104,205. (No model.)

To all whom it may concern:

Be it known that I, GEORGE L. STARR, of Otsego, in the county of Otsego, State of New York, have invented certain new and useful 5 Improvements in Culinary Lifters, of which the following is a complete specification, reference being had to the accompanying drawings.

The object of my invention is to produce a 10 cheap, simple, and efficient device for lifting a variety of heated utensils when employed as in cookery, one which is adapted when not in use for lifting purposes to constitute a convenient stand or support for heated articles 15 and one which is well adapted for handling eggs in the shell, as in boiling. My device, although specially applicable to culinary purposes, may be employed also for a wide variety of other purposes.

20 In the accompanying drawings, Figure I is a perspective view of my device in its normal position, in which it is ready for use and in which it is adapted to be used as a stand or support. Fig. II is a similar view showing 25 the device in operation as a lifter. Fig. III is a similar view showing the device in operation as an egg-lifter, the position of the prehensile member upon the frame being shifted to adapt it to that purpose.

30 Referring to the numerals on the drawings, 1 indicates one leg, and 2 the other, of the frame of my device, which, being made of wire and united at one end by means which impart to the two legs a yielding tendency to 35 separate—as, for example, a coil 3, formed in the resilient wire of which the frame is constructed—constitute a pair of tongs.

Operatively secured to the frame is a two-part prehensile member whose parts 4 and 5 40 are pivotally united to the respective legs and to each other. Each part of the prehensile member terminates in a grasping end, which in the preferred form of embodiment of my invention illustrated consists of a pair of 45 hooks 7 and 8, respectively. Each part of the prehensile member in the said preferred form of embodiment is made of a single piece of wire, bent as illustrated, and is provided upon opposite sides with eyelets 9 and 10, 50 which encircle and pivotally secure the part

to the leg of the frame upon which in practice it works. The two parts are not only pivotally united to each other, as has been specified, but are preferably provided with stop mechanism for limiting the pivotal movement of the two parts with respect to each other. By this means the prehensile member is made to constitute in its extended position (shown in Fig. I) a firm bridge across the frame, to which it is united in the manner 55 specified.

In the preferred form of embodiment of my invention, the two parts of the prehensile member being made of wire, as specified, each part is provided with a cross-piece 11 and 12, 60 respectively, formed integrally therewith. The cross-piece 11 is bent up underneath the cross-piece 12 to form eyelets 13 and 14, which encircle the cross-piece 12 and pivotally unite the two parts of the prehensile member. The 65 cross-piece 12 is provided with an upwardly-projecting bend 16, which, projecting into the path of the cross-piece 11, interrupts its movement around the cross-piece 12, and thereby constitutes the stop mechanism referred to. 70 The prehensile member is adapted to slide from one end of the frame to the other; but I prefer to limit its movement toward the free end of the legs, as by stops 18, formed in the legs by bending them. 75

At the extremities of the legs I provide in each, as by bending, a vertically-disposed ring 19. The rings not only give a finish to the article, but also afford means for using the tongs for lifting eggs and render the device available as a stand or support. 80

The operation of my device is as follows: First, the tendency of the legs to keep separated, as by the resilient action of the coil 3, tends normally to hold the device at all times 90 in the position shown in Fig. I, the prehensile member being loosely held in a fixed position upon the frame. In this position the device is adapted to be used as a stand, in which the bottoms of the rings 19, the bottom of the 95 coil 3, and the hooks 7 and 8 act as legs for the device to rest upon. In the position referred to also the device is always ready for use as a lifter. For that purpose the operator grasps the legs, as between the thumb 100

and the finger, near the coil 3, and applies the hooks about the article to be lifted—for instance, the rim of a pan 20 shown in the drawings. Then by slight pressure the legs 5 are brought together until the hooks 7 and 8 engage the rim. After engagement of the article by the hooks the article can be readily lifted, using the tongs or frame as a handle. No pressure is required to operate the device 10 after the hooks are in engagement; but the weight of the article tends to hold the parts of the prehensile member in engagement by transforming the prehensile member into a pair of lifting-tongs. A slight pressure upon 15 the legs will produce disengagement of the hooks from the article, and the separation of the legs restores the device to its normal position. The tongs can be utilized for manipulating eggs in the shell without reference to 20 the position of the prehensile member upon the legs thereof; but for convenience the prehensile member is preferably slipped toward the coil 3, thereby leaving the free ends of the legs to be used for the purpose specified, 25 in which the rings 19 readily catch and hold an egg when applied thereto under pressure, as between the thumb and finger applied near the coil 3. The stops 18 on the legs are employed in order to permit the free manipulation 30 of the prehensile member without permitting contact between the rings 19 and the contents of a dish, which might be defaced by such contact.

What I claim is—

- 35 1. A device of the kind described, comprising three distinct elements in combination, namely, a frame provided with a pair of legs and the two parts of a prehensile member, said prehensile member extending as a unit 40 transversely across the two legs, the said parts being movably secured to each other and to the legs respectively and being operative through movement of the legs.
- 45 2. The combination with a pair of tongs of a prehensile member operatively connected therewith and extending transversely across the two legs of the tongs, said prehensile member comprising two oppositely-acting parts and being movable lengthwise of the tongs.
- 50 3. The combination with a pair of tongs and a prehensile member operatively connected therewith and extending transversely across the two legs of the tongs, said prehensile mem-

ber comprising two oppositely-acting parts and being movable lengthwise of the tongs, 55 of stops for limiting said lengthwise movement.

4. The combination with a pair of tongs, of a prehensile member consisting of two parts pivotally united to the tongs and to each other 60 and provided with grasping ends comprising a pair of hooks upon each of the parts of said prehensile member.

5. The combination with a pair of tongs, of a prehensile member consisting of two parts 65 pivotally united to the tongs and to each other, grasping ends upon the prehensile member, and stop mechanism adapted to limit the pivotal movement between the two parts of the prehensile member. 7c

6. The combination with a pair of tongs and a prehensile member operatively secured thereto, of vertically-disposed rings upon the ends of the legs and tongs respectively.

7. The combination with a pair of legs 75 united by a resilient coil and provided with terminal rings, of a two-part prehensile member, the parts being pivotally united to the legs, respectively, and to each other, hooks upon the prehensile member and stop mechanism for limiting the pivotal movement of the two parts of the prehensile member, the hooks and bottoms of the rings and coil, respectively, being in the same plane when the 80 device is in normal position. 85

8. The combination with a pair of tongs comprising a pair of resiliently-separated legs, of a prehensile member comprising two parts pivotally united to the legs of the tongs, respectively, and united in like manner to each 90 other. 90

9. The combination with a prehensile member comprising two parts pivotally united to each other, of a frame provided with two members operatively united to the two parts of 95 the prehensile member, respectively, and means for actuating the prehensile member through manipulation of either end of the frame. 95

In testimony of all which I have hereunto 100 subscribed my name.

GEORGE L. STARR.
